UNITED STATES PATENT OFFICE.

JOHN STRANGE, OF NEENAH, WISCONSIN.

BUCKET-CLOSURE.

1,222,047.

Specification of Letters Patent. Patented Apr. 10, 1917.

Application filed August 3, 1915. Serial No. 43,363.

To all whom it may concern:

Be it known that I, JOHN STRANGE, a citizen of the United States, residing at Neenah, in the county of Winnebago and State of 5 Wisconsin, have invented certain new and useful Improvements in Bucket-Closures, of which the following is a specification.

My invention relates to paper pails or buckets, and particularly to the means for 10 protecting and sealing the cover upon receptacles of like character.

The object of my invention is to provide a sealing device and protector for the edge of the cover for a wooden or paper pail, bucket 15 or receptacle of like character, whereby the edge will not become broken or damaged in transit, and the sealing wires support the edge protector on the cover.

Furthermore, the object of my invention 20 is to provide means for securing the cover upon a bucket or receptacle in such a manner as to prevent the same from being removed without destroying the seal and the contents of the receptacle interfered with, 25 and the replacing of the cover so that it would be impossible to determine whether the seal had been released and any portion of the contents taken out of the bucket or pail.

30 With the above and other objects in view, my invention consists in the details and arrangement of the fastening means and protector as hereinafter more fully described and particularly pointed out in the claims.

35 In the description of my invention references will be had to the accompanying drawing, forming a part of this specification, wherein like reference characters denote corresponding parts in the several views, and 40 in which:

Figure 1 is a vertical section of a paper or wooden cylindrical shaped receptacle.

Fig. 2 is a plan view of one of the cross wires.

45 Fig. 3 is a top plan view of a bucket or pail, showing the securing wires.

Fig. 4 is a plan view, showing the securing wires in a locked position, and also the effect of the wire when bent so as to release 50 the same from the hook of the pail.

In the drawings 1 indicates the body portion of a pail, bucket or receptacle of similar character, which may be made of paper, wood, fiberoid, or similar material, but 55 preferably of paper. The body portion is provided near the lower edge with a groove,

2, in which seats the outer edge of a bottom, 3. An inner strengthening band, 4, is secured to the body portion on the inner surface against the outer edge surface of the 60 bottom. A strengthening band, 4, is secured to the body portion by any suitable adhesive means. A strengthening hoop, 5, is secured to the upper edge of the body on the outer surface and abutting against the lower edge 65 of the strengthening hoop, 5, I secure a wire hoop, 6. Below and against the lower edge of the wire, 6, I secure a hoop, 7. By such construction the wire hoop, 6, is retained between the two strengthening bands, thereby 70 preventing its accidental displacement. The wire hoop, 6, is provided with suitable ears or loop portions, 8 and 9, forming eyes located upon opposite sides, and to which a bail, 10, is secured. The wire hoop, 6, being 75 also provided with bent portions, 11, which receive the ends of the securing wires, 12-12. A cover, 14, provided with an annular shoulder, 15, and having an annular extension, 16, is secured upon the body by 80 the securing wires, 12, in the manner hereinafter described. The sealing wires, 12, are provided with notches, 13. The notches permit the ends of the wires to be easily bent around the wire hoop, 6, in the form shown 85 in Fig. 4. The notches in the wire are one of the important features of my invention, as they not only permit of the wire being bent easily around the hoop, but when it is desired to remove the securing wire, or when 90 any attempt is made to release them, the notches cause the ends of the wires to break away, thereby destroying the seal. If the securing means be interfered with during the shipping of the pail from one place to 95 another, or in any way, it will be seen that the end of the wire will be broken off and the wire cannot be again secured in place to 100 form the seal, thus indicating whether the contents of the receptacle have been tampered with while being transferred or shipped from one city to another. An annular angle shaped band, 17, seats upon the outer edge of the cover, 14, one edge of the band extending downward along the outer 105 surface of the body portion of the pail. The other edge forms a protector for the edge of the cover and supports the sealing wires. The band also prevents injury to the edge of the cover or pail, and is held firmly in place 110 by the wires, 12.

The ordinary use of pails or receptacles

of this character is for shipping candies and similar goods, and in many instances the cover has been removed and a portion of the contents taken out, the cover replaced without any indications that the pail had been interfered with, and this fact not being known until after the receiver had receipted for the same. My improved manner of securing the cover will indicate at once to the receiver whether the cover has been removed during the transportation of the same from the factory to its destination.

It is believed that the above description of my invention can be fully understood, it being noted that various changes may be made in the proportion and details of construction without departing from the scope of my invention.

What I claim as new and desire to secure by Letters Patent is:

1. In a closure for buckets, a cover provided with an annular shoulder on its inner surface, adapted to fit within the body of the pail, and having an extension extending over the upper edge of the body of the pail, an angular shaped annular rim seated on the top of said cover, a wire hoop provided with bent portions secured on the body portion of the pail adjacent its upper edge, a plurality of wires extending across said cover and having their ends secured in said bent portions of the hoop, substantially as described.

2. In a bucket closure, a cover, a hoop having bent portions secured on the body portion of the bucket, a plurality of wires extending across the cover, and having their ends inserted through the bent por-

tions in the hoop and bent upon said hoop, said wires being provided with a plurality of notches adapted to permit said wires to bend over said hoop, and cause the breaking off of the ends when said wires are released from the hoop.

3. In a bucket or pail of the character described, a wire hoop suitably secured upon said bucket at its upper edge, means for retaining said hoop on the pail, said hoop being provided with bent portions, a cover adapted to fit over the body portion of the bucket, an angular shaped metal annular ring, seated on the outer edge of said cover, a plurality of cross wires extending across the cover and having their ends inserted through the bent portions in the hoop, said end portions of the wires being provided with a plurality of notches adapted to permit of their bending around the hoop, and cause the severing of the ends of the wires when released from the hoop, as and for the purpose set forth.

4. In a bucket or pail sealing device of the character described, the combination of an angular shaped band adapted to seat upon the edge of a bucket cover, sealing wires having a plurality of notches formed near their ends, a wire hoop having bent portions adapted to receive and retain the ends of the wires, as and for the purpose set forth.

In testimony whereof I affix my signature in presence of two witnesses.

JOHN STRANGE.

Witnesses:

C. A. HECKRODT,
H. E. LANDGRAF.
